DESIGN FOR A WEATHER VANE

Henry C. Orndorff, Providence, R. I.

Application January 14, 1938, Serial No. 74,290

Term of patent 3½ years

To all whom it may concern:

Be it known that I, Henry C. Orndorff, a citizen of the United States of America, residing at Providence, in the county of Providence and State of Rhode Island, have invented a new, original, and ornamental Design for a Weather Vane, of which the following is a specification, reference being had to the accompanying drawing, forming part thereof.

Fig. 1 is a side elevation of a weather vane showing my new design.

Fig. 2 is a front elevation or edge view thereof.

I claim:

The ornamental design for a weather vane, substantially as shown.

HENRY C. ORNDORFF.
